ELECTRIC FLATIRON

Maurice F. Fitzgerald, Winsted, Conn., assignor
to The Fitzgerald Manufacturing Company,
Torrington, Conn., a corporation of Connecticut

Application July 28, 1936, Serial No. 93,074

5 Claims. (Cl. 219—25)

This invention relates to new and useful improvements in an electric flatiron provided with an automatic, heat-actuated circuit breaker, and provided also with means for adjustably limiting the degree of heat required to open the circuit.

The object of the invention is to provide an efficient and durable flatiron of the type stated, which may be economically manufactured and easily assembled.

10 It is also an object of the invention to provide a construction in which the circuit breaker arm is supported by a spring having its end embedded in an integral extension of the sole plate and is adapted to be opened by an expansion rod housed 15 within the sole plate, whereby the entire mechanism presents a very compact assembly, to which the heating element is readily connected.

The novel features of the invention and the advantages thereof will be more particularly explained in connection with the accompanying drawing, in which—

Fig. 1 is a vertical longitudinal section taken centrally of the flatiron.

Fig. 2 is a partial plan view of the invention, 25 with the cap plate removed.

Fig. 3 is an enlarged sectional view taken on the line 3—3 of Fig. 2.

Fig. 4 is a diagram of the electric circuit in the iron.

30 As illustrated in the drawing, the flatiron embodying the invention comprises a sole plate 5 formed with a comparatively thick longitudinally extending central portion 6 and with a peripheral flange 7 defining a channel 8, within which the heating element 9 is located. A horizontal plate 10 is secured to the broad upper surface of the central portion 6 by screws 11.

An insulated terminal 12 is secured to a rear corner of the plate 10 and a forwardly extending spring blade 13 carrying a contact 14 is secured to this terminal but is insulated from the plate by a mica washer 15 or the like. The plate 10 has a vertical flange 16 to which a bell crank 17 is pivoted, as at 18, to rock in a vertical plane. The rearwardly extending horizontal arm 19 of the bell crank is bent laterally, as at 20, and has a broad surface to which a circuit breaker arm 21 is secured by screws 22 and 23 and suitably insulated. The arm 21 carries a contact 24

45 which is adapted to normally engage the contact 14. The other arm 25 of the bell crank extends downwardly into a well 26 in the thickened portion 6 of the sole plate and an expansion bar 27 is mounted in a channel 28 with one end adapted

50 to engage the end of the arm 25 and the other

end adapted to be engaged by a screw-threaded adjustable plug 29.

A cap plate 30 and handle 31 are secured by screws 32 which engage threaded sockets in the heads of the screws 11. This cap plate carries 5 the usual socket 33 within which are terminal pins 34 and 35, suitably insulated from the cap plate 30 and adapted to be connected to a source of electric current. One of the pins, as 34, is connected by a conductor strip 36 to the terminal 23, which is also one of the screws which secure the arm 21 to the portion 20 of the bell crank 17. One end of the heating element 9 is connected to the terminal 12 and the other end is electrically connected to the terminal pin 35. 15

A spring 37, embedded at one end in the portion 6 of the sole plate and with its other end secured by a screw 38 to the arm 20, is so tensioned as to normally hold the circuit breaker arm 21 closed.

When the iron is in operation, as long as the contacts 24, 14 are closed, current flows from the terminal pin 34 through the conductor strip 36 to the terminal 23, thence through the arm 21, contacts 24, 14 and blade 13 to the terminal 12, 25 and thence through the heating element 9 to the terminal pin 35. When the iron becomes heated to the desired temperature, the longitudinal expansion of the bar 27 rocks the bell crank 17 and circuit breaker arm 21 against the tension of the spring 37 to open the contacts 24, 14 and break the circuit. 20

An initial adjustment of the temperature range may be effected by adjustment of the plug 29 and this may be subsequently adjusted from time to time to compensate for any wear of the contact points. A further adjustment is provided by a screw 39 mounted in the cap plate 30. The extremity of this screw bears against an insulator button 40 seated in the end of the spring blade 40 13 and the screw is provided with a handle 41 by which it may be turned to raise or lower the contact point 24 to adapt the iron for different degrees of heat.

From the foregoing description, it will be seen 45 that I have devised an automatic, adjustable electric iron, which is of simple and inexpensive construction and which may be easily assembled. All of the heat-controlling mechanism is mounted in or on the sole plate and is not in any way disturbed if the cap plate is removed for the purpose of replacing the heating element.

It will also be noted that the contact point 14 is secured to the spring blade 13 and is adjusted by direct pressure from the screw 39. The contact 55

point does not turn when the screw is adjusted. This is an important advantage because, if the points become pitted or rough, they are not thrown out of registry by the adjustment.

5 It is to be understood that the details of the present construction, as shown and described, are merely illustrative, and that the invention also embraces all such modifications as may fall within the scope of the appended claims.

10 Having thus described the invention, what I claim as new and desire to secure by Letters Patent is:—

15 1. An electric flatiron comprising a sole plate having heating means therefor, a supporting plate mounted on said sole plate, a lever pivotally mounted intermediate the ends thereof on said supporting plate and having a switch contact carried by one arm thereof, a switch arm mounted on said supporting plate and having a switch contact 20 cooperating with the switch contact carried by said lever, an expansion bar disposed in direct thermal relation with said sole plate and cooperating with the other arm of said lever to actuate the lever about its pivotal axis whereby to open 25 and close the said switch contacts upon expansion and contraction of the said bar, a cover for the flatiron, an adjustable screw mounted on said cover and bearing against said switch arm and operating to adjust the position of the contact 30 carried by said switch arm whereby to control the temperature setting of the iron, the said adjustable screw being removable with the cover independently of the said switch arm and the supporting plate, and means detachably securing said 35 supporting plate to said sole plate whereby the assembled supporting plate, lever, and switch arm may be removed as a unit.

40 2. An electric flatiron comprising a sole plate having a heating means therefor, a supporting plate mounted on said sole plate, a lever pivotally mounted intermediate the ends thereof on said supporting plate and having a switch contact carried by one arm thereof, a switch arm mounted on said supporting plate and having a switch contact 45 cooperating with the switch contact carried by said lever, an expansion bar disposed in direct thermal relation with said sole plate and cooperating with the other arm of said lever to actuate the lever about its pivotal axis whereby to open 50 and close the said switch contacts upon expansion and contraction of said bar, a cover removably secured to said sole plate independently of said supporting plate, means carried by said cover and removable therewith for adjusting the relative 55 position of the contact points whereby to control the temperature setting of the flatiron, and means detachably securing said supporting plate to said sole plate whereby the assembled supporting plate, lever, and switch arm may be removed or applied as a unit.

60 3. An electric flatiron comprising a sole plate provided with communicating substantially longitudinal and vertical recesses, a heating element for said sole plate, circuit means including the heating element and a pair of separable contact points, a supporting plate mounted on said sole plate and including a vertical flange disposed adjacent said substantially vertical recess, a bell crank lever pivotally mounted on said flange with one arm thereof extending into said substantially vertical recess, said vertical flange providing a bearing surface for said bell crank lever and determining the plane in which said bell crank lever is movable, one of said contact points being

carried by the other arm of said bell crank lever and insulated therefrom and the other said contact point being mounted on said supporting plate, spring means operating on said bell crank lever for normally holding said points in contact, 5 an expansion bar disposed in said substantially longitudinal recess and adapted to contact with one arm of said bell crank lever for causing separation of the said contact points upon expansion of said bar beyond a predetermined degree, and 10 means removably securing said supporting plate to said sole plate whereby the assembled plate, bell crank lever, and switch contacts may be removed or applied as a unit.

15 4. An electric flatiron comprising a sole plate provided with communicating substantially longitudinal and vertical recesses, a heating element mounted on said sole plate and having portions thereof disposed on opposite sides of said recesses, circuit means including the heating element and 20 a pair of separable contact points, a supporting plate mounted on said sole plate above the substantially longitudinal recess and including a substantially vertical flange disposed adjacent said substantially vertical recess, a bell crank lever 25 pivotally mounted on said flange with one arm thereof extending into said substantially vertical recess, one of said contact points being carried by the other arm of said bell crank lever and insulated therefrom and the other of said contact 30 points being mounted on said supporting plate, spring means operating on said bell crank lever for normally holding said points in contact, an expansion bar disposed in said substantially longitudinal recess and adapted to contact with one 35 arm of said bell crank lever for causing separation of said contact points upon expansion of said bar beyond a pre-determined degree, a cover removably secured to said sole plate independently of said supporting plate, and means carried by said cover and removable therewith for 40 adjusting the relative position of said contact points whereby to control the temperature setting of the flatiron.

45 5. An electric flatiron comprising a sole plate having an upstanding central portion provided with communicating substantially longitudinal and vertical recesses, said central portion defining a channel therearound for the reception of a heating element, circuit means including the 50 heating element and a pair of separable contact points, a supporting plate removably mounted on said sole plate above the substantially longitudinal recess and including an upstanding vertical flange disposed adjacent said substantially vertical recess, a bell crank lever pivotally mounted on said flange with one arm thereof extending into said substantially vertical recess, one of said contact points being carried by the other arm of 55 said bell crank lever and insulated therefrom and the other of said contact points being mounted on said supporting plate, means for normally holding said points in contact, an expansion bar disposed in said substantially longitudinal recess and adapted to contact with one arm of said bell 60 crank lever for causing separation of said contact points upon expansion of said bar beyond a pre-determined degree, a cover removably secured to said sole plate independently of said supporting plate, and means carried by said cover and removable therewith for adjusting the relative position of said contact points whereby to control the 65 temperature setting of the flatiron.

MAURICE F. FITZGERALD.
